UNITED STATES PATENT OFFICE.

REUBEN BEERNINK, OF NORTH YAKIMA, WASHINGTON.

CARBURETING APPARATUS.

1,312,228.

Application filed January 26, 1916. Serial No. 74,448.

Specification of Letters Patent. Patented Aug. 5, 1919.

To all whom it may concern:

Be it known that I, REUBEN BEERNINK, a citizen of the United States, residing at North Yakima, in the county of Yakima 5 and State of Washington, have invented certain new and useful Improvements in Carbureting Apparatus, of which the following is a specification, reference being had to the accompanying drawings.

10 This invention relates to certain improvements in carbureting apparatus and has relation more particularly to an apparatus of this general character for carbureting air, and it is an object of the invention to provide an apparatus of this general character wherein the same is operated in substantially an automatic manner.

Furthermore it is an object of the invention to provide an apparatus of this general 20 character having novel and improved means whereby the necessary air may be delivered within a mixing chamber and wherein the delivery of the hydrocarbon fluid is under control of said means.

25 The invention also has for its object to provide a novel and improved apparatus of this general character wherein is included a gas holder having a movable bell and including an air feeding device also comprising a movable bell and wherein the operation of the bell of the air compressor is under control of the bell of the gas holder.

The invention also has for an object to provide a novel and improved apparatus including an air feeding device consisting of a reciprocal member and wherein movement of the member in one direction is obtained by pressure, and whereby the movement of the member in the opposite direction is accomplished by gravity.

40 The invention consists in the details of construction and in the combination and arrangement of the several parts of my improved carbureting apparatus whereby certain important advantages are attained and the device is rendered simpler, less expensive and otherwise more convenient and advantageous for use, all as will be hereinafter more fully set forth.

45 The novel features of the invention will hereinafter be definitely claimed.

In order that my invention may be the better understood, I will now proceed to describe the same with reference to the accompanying drawings, wherein—

50 Figure 1 is a somewhat diagrammatic

view partly in elevation and partly in section illustrating a plant constructed in accordance with an embodiment of my invention;

60 Fig. 2 is an enlarged fragmentary view partly in elevation and partly in section illustrating the means for lifting the movable member of the air feeding device;

65 Fig. 3 is a sectional view taken substantially on the line 3—3 of Fig. 2, looking in the direction of the arrow;

70 Fig. 4 is an enlarged fragmentary view partly in section and partly in elevation illustrating the means for operating the controlling valve herein embodied, as employed in connection with means for moving the member of the air feeding device;

75 Fig. 5 is a sectional view taken substantially on the line 5—5 of Fig. 4;

Fig. 6 is a fragmentary view partly in section and partly in elevation illustrating the delivery pump coacting with the hydrocarbon fluid;

80 Fig. 7 is a sectional view taken substantially on the line 7—7 of Fig. 6; and

85 Fig. 8 is a fragmentary view partly in section and partly in elevation illustrating one of the guiding means herein employed in connection with the movable member of the air feeding means or the bell of the gas holder.

90 As disclosed in the accompanying drawings, 1 denotes a supply tank of predetermined capacity which is initially filled with volatile hydrocarbon, such as gasolene, said tank being provided with a filling tube 2 and drain cock 3, and supported by said tank at a predetermined point thereabove, is the mixing chamber 4 having arranged therein 95 the conical shaped strainer 5 formed preferably of a reticulated fabric and having its restricted portion disposed downwardly and with its upper end of a diameter substantially equal to the diameter of the mixing chamber 4 and terminating adjacent the top thereof.

95 P denotes a vertically disposed fuel pump having in communication therewith the induction pipe 6 and in communication with the tank 1 adjacent the bottom thereof, and also in communication with the pump P adjacent the upper end thereof is the eduction pipe 7 extending within the mixing chamber 4 through the bottom thereof and terminating within the lower portion of the strainer 5, the inner end of the pipe 7 being 100 105 110

provided, as at 8, with a spraying device. It will be at once perceived that the strainer 5 will collect the heavy vapor or mist together with any sediment.

- 5 F denotes an air feeding member herein disclosed as comprising a tank 9 with which coacts the movable member or bell 10 which, upon its descent, forces air within the mixer 4 through the pipe 11 leading from within 10 the movable member or bell 10 to the mixing chamber 4 adjacent the bottom thereof and extending through a side wall of the mixing chamber, as is particularly illustrated in Fig. 1. It is to be noted that the pipes 6, 15 7 and 11 have interposed therein the check valves 12 to prevent retrograde flow through the same, and it is also to be noted that the tank 1 and the pipe 11 have in communication therewith the return pipe 14, the point 20 of communication between the pipe 14 and the pipe 11 being intermediate the mixing chamber 4 and the check valve 12, so that the liquid collected upon the bottom of the mixing chamber 4 will return to the tank 1. 25 The return pipe 14 has interposed therein the valve 15 whereby the flow through the return pipe may be prevented except when it is desired to return to the tank 1 the liquid collected upon the bottom of the mixing 30 chamber 4.

H denotes a gas holder comprising the tank 16 and the coacting bell 17, and discharging within the bell 17 is the delivery pipe 18 leading from the mixing chamber 4 through the top thereof, and in communication with the pipe 18 is the gas main 19 having interposed therein a controlling valve 20.

When the bell 17 is in elevated position, the movable member or bell 10 is in its lowest 40 position and as the supply of gas is exhausted from the holder H, the bell 17 lowers, and as herein embodied, I provide means coacting with the bell 17 whereby the movable member or bell 10 is caused to rise 45 before the bell 17 reaches its lowermost position.

As herein embodied, the raising of the movable member or bell 10 is accomplished through the medium of the hydraulic lift L, 50 herein disclosed as comprising the vertically disposed cylinder 21 supported by one of the connecting members 22 of the rods 23 for guiding the movable member or bell 10 in its movement and positioned within the cylinder 21 is the piston 24 provided with the rod 25 extending through the lower end of the cylinder 21 and operatively engaged, as at 26, with the upper end or head of the movable member or bell 10, whereby it will be 60 perceived that as the piston 24 is forced upwardly the movable member or bell 10 will be elevated.

In communication with the cylinder 21 adjacent its lower end is the boxing or housing 27 having provided in its upper wall ad-

jacent its outer end the opening 28 under the control of the valve 29, said valve being provided with a stem 30 extending within the boxing or housing 27 through the opening 28 and having its inner extremity pivotally engaged, as at 31, with the lever 32, disposed longitudinally of the boxing or housing 27 and pivotally mounted intermediate its length, as at 33. The opposite or inner extremity of the lever 32 is pivotally engaged, as at 34, with the upstanding stem 35 of the valve 36 coacting with the discharge opening 37, said valve 36 being also provided with a depending stem 38 extending through the opening 37. As is clearly shown in Fig. 2, it is to be observed that the valves 29 and 36 are so related that one is in closed position when the other is in open adjustment.

The opening 28 is substantially defined by the upstanding annular flange or nipple 39 having in communication therewith the pipe 40 leading from a suitable source of water supply under pressure, and interposed in said pipe 40 at a predetermined point intermediate the height of the holder H is a controlling valve 41, the stem of which being provided with the arm 42 extending within the vertically disposed operating member 43 carried by the bell 17 of the holder H. The upper end of the member 43 is supported by one of the guide brackets 44 carried by the upper portion of the bell 17 and with which coact the guide rods 45, and said guide member 43 is so spaced relatively to the holder H as to overlie the tank 16 as the bell 17 descends.

As is particularly illustrated in Figs. 4 and 5, the member 43 is U-shaped in cross section and has produced in its rear wall 46 at a point adjacent its upper end, the opening 47 partially intersected by the inwardly disposed depending flange 48 which, when the bell 17 lowers, causes the arm 42 to pass through the opening 47, whereby the continued lowering movement of the bell 17 adjusts the valve 41 into an open position, whereupon the pressure of the water passing through the pipe 40 will force the piston 24 within the cylinder 21 upwardly, whereby it will be perceived that the movable member or bell 10 will be elevated, it being understood that the valve 29 is in open position.

As the member or bell 10 rises air passes 120 therein through the check controlled vent 49 in the top or head of the bell 10, and when said member or bell 10 is substantially at the limit of its upward movement, it serves to automatically close the valve 29 and open 125 the valve 36, so that the water within the boxing or housing 27 and cylinder 21 may be drained out so that no obstruction will be offered to the descending movement of the member or bell 10.

As herein disclosed, the upper end or head of the member or bell 10 is provided with the upstanding rod 50 of predetermined length and which extends through an eye 51 formed on the outer end of the rock arm 52 carried by the shaft 53 disposed transversely beneath the boxing or housing 27 and rotatably supported thereby through the medium of the depending bearings 54. The shaft 53 is also provided with the second rock arm 55 having its outer end pivotally engaged, as at 56, with the outer end portion of the depending rod 38 of the valve 36, whereby it will be perceived that as the member or bell 10 forces the rock arm 52 upwardly, the valve 29 will be moved into a closed position, while the valve 36 will be adjusted into an open position. As is disclosed in the present embodiment of my invention, the lower end portion of the rod 50 is surrounded by the expansible member 57 herein disclosed as a coil spring and which contacts directly with the eye 51.

As is believed to be fully understood, the gas delivered within the bell 17 through the pipe 18 causes the bell 17 to rise and it will therefore be readily understood that as the bell 17 moves upwardly, the member 43 will return the valve 41 to its closed position. It is to be noted that the bell or member 10 is heavier than the bell 17 so that it will be assured that the member or bell 10 will descend as the bell 17 ascends, and when the member or bell 10 has substantially reached the limit of its downward movement, the arm 52 is rocked downwardly through the medium of the expansible member 58 herein disclosed as a coil spring surrounding the upper extremity of the rod 50 and which is adapted to contact with the upper face of the eye 51. Secured to the upper end of the rod 50 is the bumper 59 herein disclosed as an inverted L, and adapted to engage the eye 51 to rock the arm 52 downward in the event obstruction from any source is offered to the operation of the lever 32 or the shaft 53.

Surrounding the shaft 53 is a balancing spring 60 having one extremity secured to the arm 52 and its opposite extremity contacting with the under surface of the boxing or housing 27 whereby movement of the rock arm 52 in an upward direction is materially facilitated.

The pump P as herein disclosed, comprises a cylinder 61 in which is mounted for reciprocatory movement the lifting piston 62 which serves to lift the liquid therein as the piston moves upward. The piston 62 is provided with the rod 63 extending through the top of the cylinder 61 and having pivotally engaged, as at 64, to its outer end the rod 65 having its upper end angularly disposed, as at 66, and terminating in the eye 67 through which the rod 68 is disposed, the

lower end of said rod 68 being angularly disposed, as at 69, and terminating in the eye 70 through which the rod 65 extends. The upper end of the rod 68 is secured to one of the guide brackets 71 carried by the upper portion of the member or bell 10 and with which the rods 23 coact. The rod 65 is provided with a plurality of longitudinally spaced openings 72 through which a cotter pin 73 or the like is directed at a point above the eye 70 of the rod 68, whereby it will be perceived that the length of the stroke of the piston 62 may be readily determined.

The rod 65 intermediate the cotter pin 73 and the eye 70 of the rod 68, is surrounded by a coil spring 74, while the lower end of the rod 65 is also surrounded by the coil spring 75 which rests upon the cotter pin 76 or the like, directed through the rod 65. The projected portion of the rod 63 is also surrounded by the coil spring 77 which rests upon the cylinder 61 of the pump P.

It will be perceived that as the member or bell 10 rises the rods 65 and 68 coact in connection with the rod 63 to lift the piston 62 to force a desired quantity of fluid within the pipe 7, and furthermore it will be perceived that as the member or bell 10 lowers the contact of the eye 70 with the spring 75 will lower the piston 62 so as to be in position for a second operation. As the rod 63 is forced downwardly it will be perceived that the spring 77 will be compressed by contact of the joint 64 with the upper end of the spring 77 so that when the member or bell 10 rises, the spring 77 will serve to impart a slight upward movement to the rod 63 until the piston 62 is pulled upwardly by contact of the eye 70 with the spring 74.

As the water is discharged through the opening 37 it is received within the pan 78 suitably supported by one of the guide rods 23 and which has in communication therewith the pipe 79 discharging into the tank 9, and said tank 9 has in communication therewith the pipe 80 leading to the tank 16 and said tank 16 is provided at a predetermined point with the overflow pipe 81 leading to a suitable point of discharge.

It will also be understood that the valve 115 mechanism coacting with the boxing or housing 27 will be actuated so as to cause a repeated rise and fall of the bell 10 as long as the position of the bell 17 is low enough to allow the valve 41 to remain open. The valve 41 will be closed to cut off the supply of motive fluid only when the bell 17 rises to a predetermined high point which will occur if the quantity of carbonated air withdrawn from the pipe 19 is less than that delivered through the pipe 18.

As herein disclosed, the guide brackets 44 and 71 are of substantially the same construction and as is particularly illustrated in Fig. 8, it will be observed that the open-

ing 82 in the guide bracket 71 through which the rod 23 passes, is provided with the anti-friction members 83, whereby a minimum of resistance will be offered to the raising and lowering of the member or bell 10.

From the foregoing description, it is thought to be obvious that a carbureting apparatus constructed in accordance with my invention is of an extremely simple and 10 comparatively inexpensive nature, and is particularly well adapted for use by reason of the convenience and facility with which it may be assembled, and it will also be obvious that my invention is susceptible of 15 some change and modification without material departure from the principles and spirit thereof and for this reason I do not wish to be understood as limiting myself to the precise arrangement and formation of 20 the several parts herein shown in carrying out my invention in practice.

I claim:

1. An apparatus of the character described including an air compressor comprising a movable member, pressure operated means for imparting movement to the movable member in one direction, a conduit leading from a source of pressure in communication with said last named means, a 25 valve interposed in said conduit for controlling the flow therethrough and including an arm, a second movable member, said member being substantially U-shaped in cross section and receiving the arm of the 30 valve, said member being provided with an opening in its rear wall at a point adjacent its upper end, an inwardly disposed depending flange partially overlying said opening, and means for imparting reverse 35 movements to the second movable member.
2. An apparatus of the character described including an air compressor comprising a movable member, pressure operated means for imparting movement to the movable member in one direction, a conduit leading from a source of pressure in communication with said last named means, a 45 valve interposed in said conduit for controlling the flow therethrough and including an arm, a second movable member, said member being substantially U-shaped in cross section and receiving the arm of the 50 valve, said member being provided with an opening in its rear wall at a point adjacent its upper end, an inwardly disposed depending flange partially overlying said opening, and means under control of the air compressor for imparting reverse movements 55 to the second movable member.

Copies of this patent may be obtained for five cents each, by addressing the "Commissioner of Patents, Washington, D. C."

3. An apparatus of the character described comprising an air feeding means including a movable member, pressure operated means for imparting movement to the movable member in one direction, said pressure means including a cylinder, a piston within the cylinder, a connection between the piston and the movable member of the air feeding means, a boxing in communication with the cylinder, a conduit leading from a suitable source of pressure in communication with the boxing, said boxing being provided with a discharge opening, a valve for controlling the communication between the conduit and the boxing, a valve for controlling the discharge opening of the 75 boxing, an operative connection between the valves whereby the same are caused to move in unison but in reverse directions, a member supported by the boxing for rocking movement and operatively engaged with one of the valves, and means engageable with the rock member for imparting movement thereto for adjusting the valves into open or closed positions.

4. An apparatus of the character described comprising an air feeding means including a movable member, pressure operated means for imparting movement to the movable member of the air feeding means in one direction, said pressure means including a cylinder, a piston within the cylinder, a connection between the piston and the movable member of the air feeding means, a boxing in communication with the cylinder, a conduit leading from a suitable source of pressure in communication with the boxing, said boxing being provided with a discharge opening, a valve for controlling the communication between the conduit and the boxing, an operative connection between the valves whereby the same are caused to move in unison but in reverse directions, a member supported by the boxing for rocking movement and operatively engaged with one of the valves, said rock member being provided with a loop, a rod carried by the movable member of the air feeding means and disposed through the loop of the rock member and provided with means whereby the rock member may be moved in opposite directions.

In testimony whereof I hereunto affix my signature in the presence of two witnesses.
